A technical drawing of a curved metal part, likely a bracket or a support. The part is shown in perspective, highlighting its curved shape and a rib extending from its top. A slot or opening is visible on the side. The drawing is labeled with numbers: 21 points to the bottom horizontal surface; 22 points to the slot; 23 points to the rib; and 24 points to the top surface of the curved part.

R. CALLIOUS J. McCARTY Inventor

S. J. Mathews Jr.

Attorney

UNITED STATES PATENT OFFICE.

CALLIOUS J. McCARTY, OF MORGANTOWN, WEST VIRGINIA.

HORSESHOEING-STAND.

1,274,727.

Specification of Letters Patent. Patented Aug. 6, 1918.

Application filed February 23, 1918. Serial No. 218,766.

To all whom it may concern:

Be it known that I, CALLIOUS J. McCARTY, a citizen of the United States, residing at Morgantown, in the county of Monongalia and State of West Virginia, have invented certain new and useful Improvements in Horseshoeing-Stands, of which the following is a specification.

This invention relates to horseshoeing-stands, and has particular reference to a novel improvement therein whereby the shoeing operation may be quickly and conveniently performed.

To this end the invention contemplates a device of the character set forth wherein the animal may be comfortably placed under a restraint without damage or injury to himself or to others, while at the same time rendering the feet of the animal to be shod conveniently accessible to the blacksmith. In this latter connection, an important feature of the present invention resides in providing a construction wherein the blacksmith may stand in a natural upright and comfortable position to accomplish the shoeing operation thus relieving him of much of the personal discomfort and irksomeness incident to a continued stooping or bending position, while at the same time rendering the manipulation of the shoes and tools more convenient and expeditious.

A further object of the invention is to provide a simple and inexpensive construction which may be made of readily available materials at a minimum expense, and which when once installed will require little or no attention, and will always be reliable and ready for use.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings in which:

Figure 1 is a top plan view of my improved horseshoeing-stand.

Fig. 2 is a vertical sectional view on the line 2—2 of Fig. 1.

Fig. 3 is a horizontal sectional view on the line 3—3 of Fig. 2.

Fig. 4 is a longitudinal sectional view taken on the line 4—4 of Fig. 3.

Fig. 5 is a detail sectional view of one of the foot rests for holding the horse's foot during the shoeing operation.

Similar reference characters designate corresponding parts through the several figures of the drawings.

The present invention primarily includes in its organization a fixed animal platform designated generally as 1 and occupying a plane on a level with the floor F of the shop, together with suitable animal restraining means, and an operator's elevator designated generally as 2 which is designed to fit into the cut-away portions 1^a of the platform and may be lowered into the operator's pit 3 below the floor level to enable the blacksmith to be lowered to a position where he may assume a natural upright position to perform the shoeing operation. Accordingly, it will be apparent that a primary feature of the present invention is the provision of an elevator which entirely surrounds the animal platform in such a manner that the animal may be readily led onto the latter from the floor level, and when held in place by means of suitable restraining devices arranged above the platform, will be held in the proper position for carrying out the shoeing operation.

Referring now more particularly to the details of construction involved in the foregoing primary features, it may be noted that there is provided a suitable framework or superstructure consisting of the upright pillars or posts 4 which extend upwardly from the pit 3 to receive the cross beams 5 that are adapted to support the mechanism for raising and lowering the elevator 2, and also the animal restraining means. In connection with the upright pillars or posts 4 at the front of the stand it will be observed that the same may be connected at their intermediate portion by the transverse cross bars 4^a, and also, an apron or guard 4^b may be provided between the plane of the lower edges of the bars 4^a and the floor level for preventing the animal from walking forwardly from the platform instead of backing off. Furthermore, it will also be observed that the cross bars 4^a support the spaced panel sections 4^c which provide a window in the front wall of the stand through which the horse's head may project, thus providing in effect a stock for the head and shoulders of the animal. That is to say,

it is proposed to provide the front of the

stand with a window opening and arrange a fastening device for the head of the animal in front of the opening so that if necessary the head of the horse can be tied through the opening with his shoulders against the panel sections of the upright members of the stock to prevent the horse from seeing the operation of the elevator and also the shoeing operation, and being alarmed thereby. And, proceeding first with a description of the animal restraining means, it will be observed that the same includes suitable frame-elements 6-6 which are suspended from the cross beams 5 and are arranged in pairs whereby their lower ends may support suitable horizontal members for forming a stall-like inclosure including means for engaging the body of the animal. These members preferably consist of the relatively stout stationary cross piece 7 carried by one pair of depending frame elements and provided with the hooks 8, and a drum or windlass 9 rotatably journaled as at 10 in the opposite pair of frame members 6-6 and adapted to be operated by any suitable means such as the pawl, ratchet, and crank mechanism *m* shown in Figs. 1 to 4 of the drawings. Detachably engaging the fixed hooks 8 on the cross piece 7 are a pair of broad belts or straps 11 whose opposite ends also detachably engage the hooks 9^a on the windlass 9, and when the animal has been led onto the stationary stand 1 the said straps or belts 11 may be placed beneath his body in such a manner as to prevent injury when the windlass is operated to reel the same taut. And, to further assist in restraining the animal, the rear end of the spaced depending frame members 6-6 have fitted thereto the breeching strap 12, while his halter may be readily engaged by the snap hook 13 of an adjustable halter strap 14 which is preferably led around a spool 15 at the front of the shoeing stand and thence around any one of a series of vertically arranged adjusting hooks 16 while the end opposite the hook 13 is fixed or secured as at 17 to the frame of the stand. This particular type of strap is especially advantageous since it enables the horse to be quickly hitched without leaving any slack in the strap and thus holding his head in the proper position.

While the above described restraining devices are provided for the body of the animal, it is also desirable that his feet be restrained during the shoeing operation particularly the foot being shod, and to this end it is proposed to provide the fixed platform 1, on each side of the central cut-way portion 1^a thereof with a pair of spaced parallel guide rails 18-18, the same being preferably of dove-tail, or equivalent cross section, as shown, for the purpose of receiving thereon a self-adjusting foot rest de-

vice R. This foot rest device R is slidably and detachably mounted on the rails 18, and any desired number thereof may be utilized at one time so that one or more feet of the horse may be shod at the same time by different blacksmiths. 70

By reference to Fig. 5 it will be observed that this foot rest essentially consists of a body portion 19 having a swivel mounting 20 on a suitable rail engaging saddle or glide 21, whereby when the foot of the animal rests upon the upper curved surface 22 of the body 19, the latter will readily adjust itself to the position of the animal's limb so as not to place the same under uncomfortable restraint. The upper surface 22 of the body 19 of the foot rest is preferably covered with some soft material such as sheep skin or the like to prevent injury to the flesh of the horse's ankle in case he 85 struggles to remove his foot from the rest, and for the purpose of holding the foot steady and in the proper position during the entire shoeing operation the said rest is preferably fitted with a suitable strap 23 or its equivalent which may have one end fixed to one side of the block 19 while the opposite end is adjustably connected therewith by means of a buckle or the like. 90

In connection with the elevator 2 which entirely surrounds the fixed animal platform 1, and is guided in its movement on the rails 2^b, it may be noted that the central inwardly projecting portions 2^a fit in the corresponding cut-out portions 1^a of the animal platform, to thereby provide a convenient point of support for the operator while shoeing the front feet of the animal. And, for the purpose of elevating the platform, the same has preferably connected therewith adjacent each corner, suitable elevating ropes or cables 24 which pass over the double pulleys 25 journaled on the cross beams 5^a at the upper part of the framework and from thence pass on to a main windlass or drum 26, to which they are secured. This windlass or drum 26 is journaled transversely of the top of the frame of the stand as at 27, and serves as a common winding drum for all of the ropes or cables 24 of the elevator 2. Further, for the purpose of counter-balancing the weight of the elevator 2 and rendering the operation of the drum 26 comparatively easy, there is also connected with each corner of the elevator a flexible member 24^a which passes over a portion of the pulley 25 and carries at its free end a suitable depending counter-balancing weight W. 110

To permit of the manual rotation of the drum 26 the same carries at one end thereof an operating device which may be of the chain and sprocket type or as shown may be a wheel 28 adapted to receive an endless operating rope or cable 29 which passes over the relatively small fixed pulley 30 mounted 120

in the pit 3 beneath the floor level. Conveniently located with respect to the rope 29 is a vertically disposed handle element 31 whose lower end is provided with a rack 32 for engaging with a suitable pawl 33 while its upper end is pivotally connected as at 34 with a brake shoe element 35, which is pivotally supported as at 36 on a bracket 37, and is adapted to engage with the operating wheel 28 to prevent the rotation of the same to maintain the elevator 2 on the level with the floor of the shop, or at any desired point between this plane and its maximum downward limit. The said brake 35 is preferably of a more or less yielding character, whereby its braking action under the influence of pressure placed on the rod 31 by the latter engaging under tension with the pawl 32, will be more effective.

From the foregoing it will be clear that the fixed animal supporting platform 1 is well equipped for holding and restraining the animal to be shod, while the elevator 2 when on the level with the floor and stand 1 permits of readily bringing the animal onto the stand and also leading him off after the shoeing operation has been completed. Furthermore, the provision of an elevator entirely surrounding the animal stand is especially advantageous since it permits of the blacksmith readily accomplishing the shoeing of all of the animal's feet in a comfortable and upright position, while at the same time greatly facilitating the shoeing operation. Also, the provision of the novel foot rest for the horse materially contributes to the general comfort of both animal and blacksmith, and saves much time and labor which would otherwise be involved in manually holding the animal's foot and resisting his struggles.

I claim:

1. A horseshoeing-stand including an animal supporting platform, and an elevator surrounding the same.
2. A horseshoeing-stand including a fixed animal supporting platform having opposite sides of its central portion cut-away, and a blacksmith's elevator entirely sur-

rounding said platform and having inwardly extending portions at its center for matching with the cut-away portions of the animal platform to provide a convenient support for the blacksmith while shoeing the animal's front feet.

3. A horseshoeing-stand including an animal supporting platform, a plurality of guide rails secured thereto, a foot rest adapted to be detachably fitted to said guide rails, means above said platform for restraining the animal, and an elevator completely surrounding said platform.

4. A horseshoeing-stand including a frame consisting of a base and a superstructure, a fixed animal supporting platform supported in said base above the level of the bottom thereof, an elevator surrounding said animal supporting platform and adapted to be shifted from the level of the animal platform to the level of the floor of the base, and means for operating and controlling said elevator.

5. A horseshoeing-stand including an animal supporting platform, an elevator surrounding the same, and means for operating said elevator including a windlass, flexible connections between each corner of the platform and the windlass, means for operating the windlass from the elevator, and a brake device for checking the rotation of the windlass.

6. A horseshoeing-stand including a stationary animal supporting platform having a plurality of supporting members each of which is adapted to carry a hoof holding device, restraining means arranged above the platform, a rising and falling support for the blacksmith including opposite parallel members operating alongside of the hoof holding positions on the animal platform, and a raising and lowering mechanism for said support for the blacksmith.

In testimony whereof I hereunto affix my signature in the presence of two witnesses.

CALLIOUS J. McCARTY.
